UNITED STATES PATENT OFFICE

2,577,314

ELECTRONIC DISCHARGE DEVICE

Eric Eastwood, Great Baddow, and John McIntyre Ferguson and Kenneth William Brown, Stafford, England, assignors to The English Electric Company Limited, London, England, a British company

Application November 17, 1948, Serial No. 60,526
In Great Britain November 19, 1947

10 Claims. (Cl. 313—56)

1

This invention relates to electron discharge devices in which a discharge is required to take place between cold electrodes in high vacuum and especially to starting the discharge in such tubes. Electron tubes, e. g. X-ray tubes, are known which are operated by discharging condensers at high voltage between metallic electrodes in high vacuum. In the event of the two main electrodes, i. e. the cathode and anode being sufficiently close together, the discharge may initiate itself, possibly by field emission. Other cases are known where voltage is applied to an auxiliary anode placed very near to the cathode to start the emission in which case a proportion of the electrons will reach the main anode. It is usual after a short period for the discharge to develop into a metallic arc of relatively low voltage.

In a discharge device according to the present invention, while similar conditions of discharge are ultimately achieved, the emission of electrons is initiated from the cathode by means of a high voltage pulse applied to a high resistance igniter element, which is in contact with the metal of the cathode. Due to the field conditions arising at the igniter-cathode interface and in the presence of a high anode accelerating potential, a very heavy discharge of electrons to the anode is initiated. With this type of cathode it is possible to reach very high currents above the range of a conventional hot cathode for a short period of the order of one microsecond. After this period the discharge passes into an arc with the normal low voltage characteristics.

With a suitable anode the device may be used as an X-ray tube and owing to the very high X-ray intensities obtainable it is possible to make radiographs with a single exposure of the order of one microsecond or less.

The invention is illustrated in the accompanying drawings in which:

Fig. 1 is a sectional elevation of an X-ray tube incorporating the invention;

Fig. 2 is an enlarged view of the cathode of the tube shown in Fig. 1;

Fig. 3 is an end view of the cathode of Fig. 2;

Fig. 4 is a typical oscillogram showing the voltage between anode and cathode in operation of the device;

Fig. 5 is an oscillogram showing the current;

Fig. 6 is a sectional elevation of a further form of X-ray tube and a schematic diagram of apparatus for supplying the operating voltage to the tube;

2

Fig. 7 is an enlarged view of the cathode of the tube shown in Fig. 6, and

Fig. 8 is an end view of the cathode of Fig. 7.

Referring first to Figs. 1 to 3, a glass envelope 1 is provided at one end with a re-entrant foot tube 2 through which is sealed a lead-in conductor 3. Mounted on the lead-in conductor 3 within the envelope 1 is a cathode 4 consisting of a block of vacuum melted copper. The end surface 5 of the cathode 4 is concave and an axial bore 6 is first drilled and then reamed in the centre of the cathode 4 for the reception of one end of a cylindrical igniter element 7. The element 7 is composed of a mass of silicon carbide crystals having a particle size of the order of 400 mesh and held together in a vitrified clay bond. The other end of the element 7 is held in the centre of a grid-like structure formed of wires 8 which in turn is carried on the end of a copper tube 9 which is fitted over the re-entrant foot tube 2 and serves as a shield around the cathode 4. Electrical connection to the tube 9 and thence to the igniter element 7 is made by means of a leading in wire 10 which is sealed through the side wall of the envelope 1 at 11. At the opposite end of the envelope 1 a further re-entrant foot tube 12 is provided through which is sealed a conductor 13 carrying an X-ray target 14. The target 14 may be of tungsten or other suitable material depending upon the nature of the X-rays which it is desired to produce. A tubular metal shield 15 is welded to the conductor 13 and surrounds the inner end of the foot tube 12. In operation of the device a high voltage pulse of the order of 250 kv. is applied across a potential divider 16 the ends of which are connected respectively to the conductors 3 and 13. The potential divider is tapped at 17 to produce a voltage of the order of 10 kv. between the igniter element 7 and the cathode 4.

Typical oscillograms of the voltage and current occurring in the operation of this tube are illustrated in Fig. 4 which shows the voltage between anode and cathode and Fig. 5 which shows the current in the device. At point B on the voltage oscillogram in Fig. 1 the metallic arc is starting to occur and the voltage begins to fall rapidly. At the same time the current correspondingly increases as is shown in Fig. 5. The current reaches a maximum when the voltage has fallen to a low value and by this time the X-radiation has practically ceased. It is beneficial that some resistance is inserted in series with the discharge tube to prevent oscillations occurring when the metallic arc has been set up.

A further form of X-ray tube according to the invention suitable for voltages of the order of 1,000,000 volts is illustrated in Figs. 6, 7 and 8. The device consists essentially of a cylindrical envelope composed of a stack of 48 porcelain rings 20 each 1" thick. The rings 20 are metallised on their end surfaces and soldered together with metal rings 21 between. A metal disc 22 having a central aperture is soldered to the topmost ring 20 and has soldered to it a ferrule 23 to which is sealed one edge of a glass cylinder 24. A lead-in conductor 25 extends through the cylinder 24 and through the aperture in the disc 22 into the interior of the envelope and is provided with a ferrule 26 which is sealed to the opposite edge of the cylinder 24. The end of the conductor 25 forms the cathode of the device and carries a dish-shaped copper shield 27. An igniter electrode 28 is embedded in the end of the conductor 25 and is carried by a grid-like structure 29 which is connected electrically to the disc 22. This construction is shown more clearly in Figs. 7 and 8. The shield 27 is conveniently formed by stamping and has a central aperture with curved shoulders to effect a measure of focussing. A threaded boss 30 is arranged co-axial with the central aperture in the shield 27 and this is screwed on to the threaded end of the conductor 25 until the end of the conductor 25 is flush with the lower surface of the shield 27 and is secured by means of a lock nut 31. The electrode 28 fits closely into a recess drilled and reamed for that purpose in the end of the conductor 25. The structure 29 is arranged to produce symmetrical field conditions and is supported by four equally spaced rods 32 extending through apertures 33 in the shield 27 and secured to the disc 22. The lower end of the tube is terminated by a flanged portion 34 which may be provided with a pumping connection 35 or may be sealed off. The member 34 carries an X-ray target 36. At the operating voltage of the device the X-radiation penetrates the target. The metal rings 21 are each provided with a terminal lug connected to a resistance potential divider 38 having a total resistance of about 3000 ohms and serve to accelerate electrons from the cathode to the target 36. In practice the terminal lug on each successive ring is displaced 90° from the lug on the preceding ring and the potential divider 38 is arranged helically around the outside of the envelope of the device since otherwise the current in the divider 38 will deflect the electrons within the envelope. For convenience of illustration, however, the potential divider 38 is shown as being arranged down one side of the envelope.

The supply and control circuit for the tube consists of a Marx generator comprising a supply transformer 39 supplying rectifiers 40 and 41 through a condenser 42. The rectifiers 40 and 41 are arranged to charge a number of condensers 43 in parallel through resistances 44 and spark gaps 45 are arranged so that the condensers 43 may discharge in series. The control circuit includes a transformer 46 having a switch 47 in its primary circuit, its secondary serving to charge a condenser 48 through a rectifier 49 and resistance 50. A spark gap 51 is provided so that the condenser 48 may discharge through the primary of an air-cored step-up transformer 52. The secondary of the transformer 52 is connected between the grounded end of the Marx generator and an electrode 53.

in the first spark gap 45. The first spark gap 45 may thus be induced to break down at a lower voltage than the remainder of the spark gaps in the Marx generator whereupon the voltage across the succeeding spark gaps will become such that they also will break down. The negative end of the generator is connected through a further spark gap 54 to the conductor 25 and to the cathode end of the potential divider 38. The positive end of the Marx generator is earthed and is also connected to the target 36. The disc 22 and consequently the igniter electrode 28 is connected to an intermediate point on the potential divider 38 such as to provide a voltage positive with respect to the cathode. A high gradient is produced at the junction of the igniter electrode and the cathode sufficient to give rise to emission of electrons. The optimum igniter voltage varies from about 7 to 15 kv. according to the length of the igniter.

It will be appreciated that the invention is not restricted to X-ray tubes and that in the case of the tube illustrated in Fig. 6 the target 36 may be omitted and the bottom of the member 34 may be in the form of a Duralumin window, for example, 0.001" thick through which the electron beam may penetrate into the atmosphere below. Alternatively, the device may be used as a control tube.

What we claim as our invention and desire to secure by Letters Patent is:

1. A high vacuum electron discharge device including an evacuated envelope, an anode and a cathode within said envelope, said cathode consisting of a body of metal in the solid state, and an igniter electrode of high resistance material, one portion of which is in intimate contact with said cathode, and another portion of which is connected to a terminal for a source of control impulses.

2. A high vacuum electron discharge device including an evacuated envelope, an anode, a cathode comprising a body of metal in the solid state, and an igniter electrode of high resistance material one portion of which fits closely in a recess in the metal of said cathode, and another portion of which is connected to a terminal for a source of control impulses.

3. A high vacuum electron discharge device including an evacuated envelope, an anode, a cathode comprising a body of metal in the solid state, and an igniter electrode in the form of a rod of silicon carbide crystals held together in a vitrified clay bond, an end of said rod fitting closely in a recess in the metal of said cathode, the other end connected to a terminal for a source of control impulses.

4. A high vacuum electric discharge device including an evacuated envelope, an anode, a cathode comprising a mass of metal, and an igniter electrode in the form of a rod of silicon carbide crystals of the order of 400 mesh held together in a vitrified clay bond, an end of said rod fitting closely in a recess in the metal of said cathode.

5. A high vacuum electron discharge device including an evacuated envelope, an anode, a cathode consisting of a body of metal in the solid state, and a symmetrical grid-like structure supported on conductors extending through apertures in said cathode and carrying an igniter electrode of high resistance material, a portion of which electrode is in intimate contact with said cathode, the portion which is in contact

with said grid-like structure connected thereby to a source of control impulses.

6. A high vacuum electron discharge device as claimed in claim 5 wherein said portion of said igniter electrode fits closely in a recess in said cathode.

7. A high vacuum electron discharge device including an evacuated envelope, an anode, a copper cathode and an igniter electrode composed of a rod of silicon carbide crystals held together in a vitrified clay bond, one end of said rod fitting closely in a recess in said cathode, the other end being connected to a terminal for a source of control impulses.

8. A high vacuum electron discharge device 15 including an elongated evacuated envelope, an anode, a cathode consisting of a body of metal in the solid state, an igniter electrode composed of a rod of silicon carbide crystals held together in a vitrified clay bond one end of which fits 20 closely in a recess in said cathode, the other end being connected to a terminal for a source of control impulses and a plurality of accelerating electrodes arranged between said cathode and said anode.

9. An X-ray generator, including an evacuated envelope, a cathode consisting of a body of metal in the solid state, an igniter electrode composed of a rod of silicon carbide crystals in a vitrified clay bond one end of which fits closely 30 in a recess in said cathode, and an X-ray producing target electrode, and another portion of which is connected to a terminal for a source of control impulses.

10. An X-ray generator including an elong- 35

gated evacuated envelope, a cathode consisting of a body of metal in the solid state, an igniter electrode comprising a rod composed of silicon carbide crystals held together in a vitrified clay bond one end of which rod fits closely in a recess in the metal of said cathode, the other end being connected to a terminal for a source of control impulses, an X-ray producing target electrode, and a plurality of accelerating electrodes arranged between said cathode and said target electrode.
